United States Patent Office

Des. 221,231
Patented July 20, 1971

221,231

MOTOR VEHICLE MOUNTED ELECTRICAL COMMUNICATION UNIT OR SIMILAR ARTICLE

Philip L. Brooks, Menlo Park, Calif., assignor to
Sylvania Electric Products Inc.

Filed Apr. 2, 1970, Ser. No. 22,218

Term of patent 14 years

Int. Cl. D14—03

U.S. Cl. D26—14

FIG. 1

FIG. 2

FIG. 3

FIG. 4

FIG. 5

FIG. 1 is a top view of a motor vehicle mounted electrical communication unit or similar article showing my new design;

FIG. 2 is a front elevational view thereof;

FIG. 3 is a right side elevational view thereof;

FIG. 4 is a left side elevational view thereof; and

FIG. 5 is a rear elevational view thereof.

I claim:

The ornamental design for a motor vehicle mounted electrical communication unit or similar article, as shown.
